ROTARY BRUSH

Joseph Alphonse Turcotte, Montreal,
Quebec, Canada

Application June 17, 1933, Serial No. 676,385

2 Claims. (Cl. 15—23)

This invention relates to a rotary brush and the principal object is to provide a new and useful article, which may be particularly advantageous for brushing or massaging hair, although I 5 do not wish to be limited to the use of the hair as the device may be used for many other purposes.

A further object is to provide a rotary brush in the construction of which the motor is fixedly supported relative to the handle and is enclosed 10 in a brush carrying member rotatably mounted relative thereto and upon which brushes may be removably mounted for rotation therewith.

A further object is to provide a rotary brush of simple construction and wherein the respective 15 parts are of such a nature that they may be assembled in compact relationship and may be easily and quickly disassembled when desirous of cleaning, oiling or for the interchanging of brushes.

20 With the foregoing and other objects in view, as will appear as the description proceeds, the invention consists of the novel construction, combination and arrangement of co-operating elements as hereinafter more specifically set forth, 25 claimed and shown in the accompanying drawing forming a part of the present application, in which:—

Fig. 1 is a top plan view of the preferred embodiment of my invention.

30 Fig. 2 is a longitudinal sectional view taken on the line 2—2 of Fig. 1.

Fig. 3 is an end view looking towards the free end of the handle.

35 Fig. 4 is an end view looking towards the opposite end of my device from that shown in Fig. 3.

Fig. 5 is a side view of the cover-bearing plate for the inner end of the brush carrying member.

40 Fig. 6 is a longitudinal section view of the mounting arrangement between the handle and the motor of my device.

Like numerals of reference designate corresponding parts throughout the different views.

7 is a handle having a longitudinal opening therein through which the electric wires 8 extend to supply electrical energy to the motor referred to hereinafter. 9 is a bracket, the body portion of which is cylindrical in shape and has an inner circumference designed to engage tightly over the inner end of the handle 7. The cylindrical 45 portion of the bracket 9 is abruptly enlarged as at 10 to provide a shoulder, the purpose of which is referred to hereinafter. The inner end of the bracket 9 is formed with a plurality of supporting legs 11, upon which the motor 12 is fixedly mounted and supported relative to the handle 7. The

ends of the electric wires 8 are suitably connected to the motor 12. The shaft 14 of the motor protrudes outwardly a reasonable distance at the end opposite to that adjacent the handle 7.

15 is a hub keyed to the protruding end portion of the shaft 14. 16 is a brush carrying member of cylindrical form, having an integral end plate 17 formed integral or suitably attached to the hub 15. This end plate 17 is provided with a plurality of draft openings 18 formed therein to permit passage of air therethrough for keeping the motor 12 cool. 19 is a cover-bearing plate having an L-shaped flange 20 providing an annular base and stop respectively for the open end of the brush carrying member 16. The open end of the 15 brush carrying member 16 is provided with an outwardly extending flange 21 designed to fit against the outwardly protruding portion of the L-shaped flange 20 and be fixedly attached thereto by means of the bolts or screws 22. The cover-bearing plate 19 is provided with a central annular opening. The cover-bearing plate 19 (preferably) carries a ball-bearing arrangement 23 designed to snugly fit and rotate on the ball-bearing race 24 mounted and supported on the bracket 25 9 adjacent the abrupt shoulder 10. The ferrule 25, adjustably carried on the inner end of the handle 7 and fitting over that portion of the cylindrical bracket 9 that engages over the inner end of the handle 7, retains the cover-bearing plate 19 30 and its associate parts, the ball-bearing arrangement 23 and the ball-bearing race 24, tightly against the abrupt shoulder 10 of the brackets 9.

The cylindrical body portion of the brush carrying member 16 is provided with raised portions 26, 35 which portions are formed opposite each other and at an angle corresponding to each other. They may be formed any place around the cylindrical portion of the brush carrying member 16 and there may be more than two opposite each other if so desired. 27 is a brush foundation portion of cylindrical formation, which preferably has a metallic backing 28 of cylindrical formation fixedly attached thereto. The metallic backing 28 and brush foundation portion 27 are preferably formed with co-acting grooves 28' relative to the raised portion 26 hereinbefore mentioned so that the brush foundation backing 27—28 may be shoved longitudinally over the brush carrying member 16 and with a slight turn will provide engagement therewith against longitudinal displacement. The purpose of having these grooves angularly disposed is so that the brush foundation backing 27—28 will have a constant and inward screw thrust towards the outwardly extend- 55

ing flange 21 of the brush carrying member 16 when being rotated upon operation of the motor 12. Any other desired means may be employed to prevent longitudinal movement of the brush foundation backing 27-28 when placed in operative position.

The brush foundation 27 carries and radially supports bristles 29. I do not wish to be limited precisely in regard to the brush foundation member or any particular kind of bristle or their equivalent. Bristles of various stiffness may be assembled with the brush foundation 27 so as to provide a variety of brushing possibilities. Also, the bristles may be hair, fibre, rubber, wire, steel or any other of the many variations commonly used in building up brush structures for many and different uses.

30 is a guard covering over approximately one-half of the rotary brush hereinbefore described. The outer edge of the guard is flanged inwardly as at 31. The inner end of the guard is closed by the end member 32, having draft openings therethrough and the central portion thereof straddling over the ferrule 25. This central portion is provided with an outwardly directed flange 33, which is engaged in any desired manner to the ferrule 25 and fixedly supported relative to the handle 7.

The cover-bearing plate 19 is provided with a plurality of angularly disposed draft openings 34 which, when rotating, will draw the air in to the brush carrying member in which the motor is enclosed. The air will escape at the opposite end through the openings 18. In the construction as above described, the motor 12 and guard 30 are mounted in fixed relative position to the handle 7 while the brush retaining member 16 and the brush 27-28-29 are rotatably mounted relative thereto with both ends of the same supported relative to a common axial centre.

The foregoing specification and annexed drawings disclose the preferred embodiment of my in-

vention, but it is to be understood that minor changes may be resorted to in the commercial adaptation of my invention without departing from the scope of the invention as hereinafter claimed.

5

What I claim as new is:

1. A rotary brush, comprising a handle; a motor supported from said handle; a brush carrying member enclosing said motor; said brush carrying member having a connection at one end with and being driven by the drive shaft of said motor; the opposite end of said brush carrying member being rotatably supported relative to said handle; a brush supported on and carried by said brush carrying member; a co-engaging helical ridge and groove connection between the outer surface of said member and the inner surface of said brush; and a radially projecting shoulder at one end of said member against which shoulder said brush abuts, whereby said brush may be readily attached to and detached from said member, but whereby rotation of said brush by the motor tends to merely tighten said connection.

2. In a motor driven rotary brush having a handle and a driving motor mounted thereon, a brush mounting assembly comprising a cylindrical brush carrying member enclosing the motor, means at one end of said member for establishing a driving connection with the motor, means at the opposite end of said member for rotatably supporting said member upon the handle, a cylindrical brush snugly fitting over the exterior of said member, and means for removably mounting said brush on said member comprising disengageable guide means carried by said member and said brush cooperating to move said member and brush axially with respect to each other upon relative rotation thereof, and stop means to limit such axial movement, whereby rotation of said brush by the motor tends to merely tighten the connection between said member and brush.

JOSEPH ALPHONSE TURCOTTE.
